METALLURGICAL APPARATUS

Luther W. Bahney, Elizabeth, N. J., and Alfred H. Horswell, Jackson Heights, N. Y., assignors to Scovill Manufacturing Company, Waterbury, Conn., a corporation of Connecticut

Application August 11, 1942, Serial No. 454,392

17 Claims. (Cl. 266—38)

This invention relates to metallurgical apparatus, in particular to apparatus for transferring, heating, or pouring molten metal, and has for an object the provision of improvements in this art.

In our Patent No. 2,195,071 of March 26, 1940, we showed an induction furnace which poured metal through its supporting trunnion into receiving vessels such as vertical molds, the metal in the furnace being heated by an electric induction heating unit to keep it molten. Means were provided within the furnace for deoxidizing the metal, which was delivered to the furnace by an open launder.

According to the present invention a furnace of the same general type and used in the same general setting, is modified in various ways, to make it more suitable for certain purposes. The principal modification is that the metal receiving assembly is constructed to positively protect the metal, and the tilting assembly is constructed to furnish more accurate control of the pouring of the metal.

The objects of the invention and various features of novelty will be apparent from the following disclosure of an exemplary embodiment of the invention, reference being made to the accompanying drawings thereof wherein:

Fig. 1 is a side view of apparatus embodying the invention;

Fig. 2 is a top plan view;

Fig. 3 is a vertical section taken on the line 3—3 of Fig. 2, with the furnace in its lowest position;

Fig. 4 is a similar section with the furnace in its highest position.

Fig. 5 is a partial section taken approximately on the line 5—5 of Fig. 3;

Fig. 6 is a partial section taken approximately on the line 6—6 of Fig. 4;

Fig. 7 is a vertical section taken on the line 7—7 of Fig. 6;

Fig. 8 is a vertical section taken on the line 8—8 of Fig. 6;

Fig. 9 is a partial vertical section taken on the line 9—9 of Fig. 5;

Fig. 10 is a partial vertical section taken on the line 10—10 of Fig. 5; and

Fig. 11 is an enlarged side view of a sealing plate seen in Figs. 3 and 4.

Referring to the drawings, the apparatus comprises a metal furnace 10, a fully enclosed supply launder 11, and a completely enclosed discharge device 12. The supply launder is fixed in position, and is connected with the furnace by a

joint which maintains a seal for a protecting gas in all adjusted positions of the furnace and launder. The furnace is mounted to tilt upon trunnions 13, one of which is tubular throughout its length, for pouring metal into the discharge device 12. This supplies the metal at substantially a fixed position in a steady stream.

The pot or chamber 14 of the furnace is disposed below the trunnion axis C, and at the bottom connects with the loop channel 15 of an electric induction heating unit 16. The central plane of the channel 15 is parallel with the axis C of the furnace trunnions, and the plane of the lower side of the channel is directed approximately toward the furnace axis, slightly behind it as seen in Fig. 3.

The shell 20 of the furnace chamber is provided with a curved extension or tail 21 projecting downward, and backward from the front side of the furnace, and the cam-like face of this extension, is adapted to cooperate with a vertically movable thrust member 22 for tilting the furnace. The thrust member shown herein is a roller secured on the end of a piston rod 23, extending vertically from a piston inside a fixed vertical cylinder 24. The curve of the cam face of the tail relative to the shape and disposition of the metal chamber, is so selected that for equal vertical movements of the piston, approximately equal amounts of metal are poured from the furnace.

The shell or casing 28 of the transformer is provided with a flange 29, by which it is secured to the flange 30 of the furnace shell, and the transformer shell is insulated from the furnace shell, as by insulation placed between the flange 29 and an auxiliary flange 31 of the transformer shell, the insulation conveniently being secured before the transformer shell is attached to the furnace shell. This flange and insulation construction is shown in detail in the patent of David L. Summey, No. 2,102,582, December 14, 1937. The transformer flange 31 is separated from the furnace shell flange 30 by a mica gasket. This gasket is used to promote a clean separation of elements 30 and 31 when the induction unit and casing 28 is removed from the furnace. It may serve as thermal and electrical insulation but is not used primarily for this purpose.

The transformer may be partly supported by adjustable set screws 32, secured in anchorages in the tail of the furnace.

The sealing joint between the supply launder and the furnace, comprises a curved top seal 35, formed as a widened continuation of

the shell of the launder on an arc concentric with the trunnion axis, the sides of the top plates being further extended as concentric side flanges 38, which fit in arcuate slots 37 in side plates 38 of the furnace shell cover 39. The cover 39 closes the space at one end of the curved top plate 35, and this may be provided with a glass sight opening 40, giving a view of the inflowing stream of metal from the lip 41 of the launder, and also of the trunnion zone in the furnace, it being noted that the launder lip is disposed above and slightly behind the trunnion axis.

The bottom wall 42 of the launder casing, fits between the side plates 38 of the furnace, and terminates in a transverse edge 43. To this edge 43 there is hinged at 44 a swingable bottom seal plate or flap 45, which also fits between the furnace side plates 38, and bears against the front transverse edge 46 of the furnace. The flap is kept pressed against the edge by any suitable means, as for example by a weight 47. As shown, the weight is suspended on a cable 48, which passes over a pulley 49, mounted on the bottom edge of the flap, the end of the cable being attached to the body of the furnace. The horizontal component of the weight increases as the effective lever arm of the flap decreases, thus tending to keep the pressure of the flap against the lip uniform.

By this arrangement the supply launder connection with the furnace is kept sealed in all tilted positions, and no openings are made in the furnace shell which will at any time be in a position to permit spillage of metal.

As shown in Fig. 6, metal is poured from the furnace by a tubular pouring spout 55, which is concentric with the turning axis C of the furnace. Consequently the metal from the spout will always fall on a fixed line vertically beneath the axis C. It may fall into any desired receiving device, such for example, as the pouring diverter or strainer 56, which leads the metal to the discharge launder 57. The pouring metal is kept free of air by the enclosure 12, which has a sealing joint with the spout 55.

The sealing joint includes a sleeve 58 surrounding the spout, which is provided with a flange 59, by which it is secured to a flange 60 formed on the furnace casing. A second sleeve 61 fits the outside of sleeve 58, and is provided with a flange 62 adjacent the flange 59. Springs 63, placed on rods 64, secured in flange 59, push the flange 62 and sleeve 61 away from flange 59. The rods 64 may be provided with adjusting nuts 65, and movement limiting nuts 66. The front end of the outer sleeve 61, has a spherical joint seal 67 with a plate 68, which fits tightly against the casing of the enclosure 12.

The enclosure 12 is heat-insulated, and heated by suitable means, to keep the stream of metal in a molten condition. The heating means shown herein comprises resistance heating elements such as "globars" 70 arranged in pairs, and protected from splashing metal by shields 71 of a material such as silicon carbide or graphite, which retains protecting gas about the metal but keeps it from the resistors, at the same time conducting heat efficiently from the resistors to the metal. A sight opening glass 72 permits a view of the stream of metal within the enclosure.

The pouring enclosure, furnace, and supply launder may be filled with an inert or deoxidizing gas under pressure. For copper, a gas composed of a considerable percentage of carbon monoxide may be used. In addition a protective covering

S may be maintained on the metal in the furnace. For copper a charcoal cover may be used.

In order to keep this covering material from passing out the spout with the metal, a skimmer 55 may be employed to shield the inner end of the spout opening 55. As shown in Figs. 5, 9 and 10, the front side of the chamber 14 is formed with a raised lip or dam 76, which retains the metal when the furnace is tilted toward the draining position shown in Fig. 4. Considering the furnace to be in the draining position of Figs. 4 and 9, this front side is also formed with sloping faces 77 and 78, which cause the metal to flow toward a transverse line or gutter 79 located at a distance from the dam. A channel or duct 80 on the spout side of the furnace, slopes downward from the line 79 to the inner end of the spout opening 55. The skimmer 75 is set at an angle over the channel 80, and covers all but the lower end near the line 79, thus permitting metal to flow out freely, but retaining the covering material.

The transformer 16 may be cooled by air from a conduit 85, which is hinged for turning movement in a joint 86 concentric with the furnace axis C, and opposite the pouring spout. The furnace shell construction at the turning axis, is symmetrical whereby the pouring spout and air joint may be placed in reverse positions, the interior lining 87, of course, being altered to place the pouring duct and skimmer in correct position relative to the spout.

The operation of the device will be understood from the above description. While one embodiment of the invention has been described to convey an understanding of the principles of the invention, it is to be understood that the invention may have various embodiments within the limits of the prior art and the scope of the subjoined claims.

40 We claim as our invention:

1. Metallurgical apparatus comprising in combination, a furnace chamber enclosure mounted to turn about a transverse axis, an enclosed pouring spout on said axis, an enclosed supply launder entering the furnace enclosure above and transverse to said axis, and a jointed connection between the launder enclosure and the chamber enclosure for maintaining a seal in all positions of the furnace.

50 2. Metallurgical apparatus comprising in combination, a furnace chamber enclosure mounted to turn about a transverse axis, an enclosed pouring spout on said axis, an enclosed supply launder entering the furnace enclosure above and transverse to said axis, and a jointed connection between the launder enclosure and the chamber enclosure for maintaining a seal in all positions of the furnace, said jointed connection including a curved top sealing plate operating between parallel sides and a transverse edge, and a bottom sealing plate operating between parallel sides and a transverse edge.

3. Metallurgical apparatus comprising in combination, a furnace chamber enclosure mounted to turn about a transverse axis, an enclosed pouring spout on said axis, an enclosed supply launder entering the furnace enclosure above and transverse to said axis, and a jointed connection between the launder enclosure and the chamber enclosure for maintaining a seal in all positions of the furnace, said jointed connection including a curved top sealing plate on the launder operating between parallel sides and a transverse edge on the furnace, and a bottom sealing plate hinged to the launder operating

between parallel sides and a transverse edge on the furnace.

4. Metallurgical apparatus comprising in combination, a furnace chamber enclosure mounted to turn about a transverse axis, an enclosed pouring spout on said axis, an enclosed supply launder entering the furnace enclosure above and transverse to said axis, and a jointed connection between the launder enclosure and the chamber enclosure for maintaining a seal in all positions of the furnace, said jointed connection including a curved top sealing plate on the launder operating between parallel sides and a transverse edge on the furnace, a bottom sealing plate hinged to the launder operating between parallel sides and a transverse edge on the furnace, and means for pressing the bottom sealing plate against the transverse edge.

5. Metallurgical apparatus comprising in combination, a furnace chamber enclosure mounted to turn about a transverse axis, an enclosed pouring spout on said axis, an enclosed supply launder entering the furnace enclosure above and transverse to said axis, and a jointed connection between the launder enclosure and the chamber enclosure for maintaining a seal in all positions of the furnace, said jointed connection including a curved top sealing plate on the launder operating between parallel sides and a transverse edge on the furnace, a bottom sealing plate hinged to the launder operating between parallel sides and a transverse edge on the furnace, and means for pressing the bottom sealing plate against the transverse edge, said means comprising a weight suspended by a cable passing over a pulley on the bottom edge of the plate.

6. Metallurgical apparatus comprising in combination, a furnace chamber enclosure mounted to turn about a transverse axis, an enclosed pouring spout on said axis, an enclosed supply launder entering the furnace enclosure above and transverse to said axis, and a jointed connection between the launder enclosure and the chamber enclosure for maintaining a seal in all positions of the furnace, said jointed connection including a curved top sealing plate on the launder operating between parallel sides and a transverse edge on the furnace, a bottom sealing plate hinged to the launder operating between parallel sides and a transverse edge on the furnace, and means for pressing the bottom sealing plate against the transverse edge, said means comprising a weight and a cable suspending the weight below the plate, the cable being attached to the furnace at one end at a point which provides increased pull of the plate against the transverse edge on the furnace as the length of the plate below said edge decreases.

7. Metallurgical apparatus comprising in combination, a furnace chamber enclosure which is mounted to turn about a transverse axis, a pouring spout on said axis, a supply launder disposed above and transversely of said axis, and a connection between said enclosure and said launder, which includes a turning joint concentric with said transverse axis.

8. Metallurgical apparatus comprising in combination, a furnace chamber enclosure mounted to turn about a transverse axis, an enclosed furnace pouring spout on said axis, and an enclosed supply launder having its pouring lip disposed above the axis and above the metal level, said launder enclosure being connected to the

furnace enclosure by a sealing joint concentric with the furnace axis.

9. Metallurgical apparatus comprising in combination, a furnace chamber enclosure mounted to turn about a transverse axis, a furnace pouring spout on said axis, and a supply launder having its pouring lip disposed above the axis and above the metal level, said launder being connected to the furnace by a joint concentric with the furnace axis.

10. Metallurgical apparatus comprising in combination, a furnace chamber enclosure mounted to turn about a transverse axis, a curved arm on said furnace enclosure extending downward and backward therefrom below said axis, and a vertically moving member for acting on the curved surface of said arm to tilt the furnace.

11. Metallurgical apparatus comprising in combination, a furnace chamber enclosure mounted to turn about a transverse axis, a cam arm secured on said furnace enclosure, said cam arm extending downwardly and laterally from said axis and lying in a plane perpendicular to said axis, and a power member which moves transversely to said cam arm and at a distance from said axis, for acting upon said cam arm to tilt the furnace.

12. Metallurgical apparatus comprising in combination, a furnace turning about a transverse axis and having a pouring spout along said axis, the furnace having a chamber which, considering the furnace in the elevated pouring position, is formed with a transverse gutter spaced from and generally parallel with the axis, and a channel sloping from one end of said gutter to the pouring spout.

13. Metallurgical apparatus comprising in combination, a furnace turning about a transverse axis and having a pouring spout along said axis, the chamber of said furnace having one lower side generally parallel with and directed approximately toward said axis in such relative position that said lower side is raised to the height of said spout when the furnace is raised to its highest pouring position, whereby to discharge all of the metal in the furnace through said spout.

14. Metallurgical apparatus comprising in combination, a furnace turning about a transverse axis and having a pouring spout along said axis. The chamber of said furnace having one lower side generally parallel with and directed approximately toward said axis in such relative position that said lower side is raised to the height of said spout when the furnace is raised to its highest pouring position, whereby to discharge all of the metal in the furnace through said spout, and a skimmer disposed above and spaced from said side and open at the bottom to permit metal to flow to said spout while retaining floating material until the furnace has been substantially emptied.

15. Metallurgical apparatus comprising in combination, a furnace turning about a transverse axis and having a pouring spout along said axis, the chamber of said furnace having one side generally parallel with and directed approximately toward said axis, and having surfaces on said side sloping toward a depressed line spaced from and parallel with said axis.

16. Metallurgical apparatus comprising in combination, a furnace turning about a transverse axis and having a pouring spout along said

axis, the chamber of said furnace having one side generally parallel with and directed approximately toward said axis, said side having a dam at the upper end above the axis.

17. Metallurgical apparatus comprising in combination, a furnace turning about a transverse axis and having a pouring spout along said axis, the chamber of said furnace having one side generally parallel with and directed

approximately toward said axis, said side having a transverse gutter spaced from said axis, a channel between said gutter and said spout, and a skimmer over said channel, said skimmer closing the channel from the furnace chamber at the upper end but leaving it open at the lower end.

LUTHER W. BAHNEY.
ALFRED H. HORSWELL.
